UNITED STATES PATENT OFFICE.

GUSTAV LENTZ, OF DUSSELDORF, GERMANY, ASSIGNOR TO THE ACTIEN-
GESELLSCHAFT FUER LOCOMOTIVBAU HOHENZOLLERN, OF SAME
PLACE.

TANK-LOCOMOTIVE.

SPECIFICATION forming part of Letters Patent No. 231,337, dated August 17, 1880.

Application filed June 7, 1880. (No model.) Patented in Germany August 2, 1879, in Belgium August 27, 1879, in Denmark March 16, 1880, in France August 28, 1879, in Great Britain August 30, 1879, in Italy September 30, 1879, in Austro-Hungary December 31, 1879, and in Sweden October 4, 1879.

To all whom it may concern:

Be it known that I, GUSTAV LENTZ, a subject of the King of Prussia, residing at the city of Dusseldorf, in the German Empire, have invented certain new and useful Improvements in Tank-Locomotives; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to a novel combination and arrangement of the steam-cylinders and drive-wheel axles of tender-locomotives, more especially designed for high speed; and it consists, essentially, in the relative arrangement and combination of the drive-wheel axles, the steam-cylinders, their piston and driving rods, with the fore and aft coupled drive-wheels, substantially as hereinafter more fully described.

Many efforts have been made, heretofore without good results to construct tender-locomotives for high speed, and such results can only be obtained, with widely-separated drive-wheel axles, by avoiding as much as possible overhanging structural masses and in so locating the cylinders as to avoid the jerking action of the piston-rods on the crank or wrist pins, and the consequent irregular movement of the machine.

If the steam-cylinders are located above the drive-wheel axles, as is the case with all such locomotives now, it is an impossibility to locate the drive-wheel axles far apart, and hence their axles are located comparatively near each other, in order to obtain a sufficiently long driving-rod, and avoid as much as possible the jerking action upon the wrist pins; and this necessitates the use of runners, as in the Crampton and other systems, while

such locomotive-tenders are not adapted for 45 high speed.

In the accompanying drawings, Figure 1 is a side elevation, and Fig. 2 a plan view, both partly in section, illustrating the application of my invention.

The tender-locomotive may be constructed in any preferred manner and of any desired pattern or style, as I do not claim any improvements in the construction of such locomotives, except in so far as the peculiar arrangement of steam-cylinders relatively to the drive-wheel axles is concerned; and in the above drawings A and B represent the fore and aft drive-wheels, respectively, and A' and B' their respective axles, the latter, B', being located behind the fire-box in order to increase the distance as much as possible between said axles and dispense with the usual runners.

C are the steam-cylinders, located on the main frame F of the locomotive, between the said frame and the connecting-rods D, that connect the drivers together, and between the axles of said drivers, either in a horizontal position or in a slightly-inclined position, but as near as possible in the plane of motion of the connecting-rods D.

The piston-rods and slide-valve rods are connected in any usual manner, respectively, to the wrist-pin b of the rear drive-wheel and to the axle of the latter.

It will be apparent that by means of the above-described relative arrangement of steam-cylinders and coupled drive-wheel axles I am enabled to dispense with the usual runners, do away with overhanging structural masses, obtain a perfectly smooth and even working of the drive-rods and piston, and adapt the tender-locomotive to high-speed service better than any machine of this class heretofore constructed.

Having now described my invention, what I claim, and desire to secure by Letters Patent, is—

50

55

75

85

In a tender-locomotive, the combination, with the main frame, the fore and aft drivers, and their axles, the axle of the latter being located in rear of the fire-box, the connecting-rods D, and the usual crank-rods, connected with the wrist-pins of the rear drive-wheels, of the steam-cylinders C, located in, or practically in, the plane of motion of the coupling-rods, and between the latter and the

main frame, all constructed and arranged substantially as described, for the purpose specified.

In testimony whereof I affix my signature in presence of two witnesses.

GUSTAV LENTZ.

Witnesses:

L. MOTIG,

FRIEDR. WENCKE.
